US00D483294S

(12) **United States Design Patent** (10) Patent No.: **US D483,294 S**
Uehara (45) Date of Patent: ** Dec. 9, 2003

(54) **BELT ADJUSTER**

JP 936321 10/1995
JP 1029594 1/1999

(75) Inventor: **Ryoichiro Uehara**, Tokyo (JP)

* cited by examiner

(73) Assignee: **YKK Corporation**, Tokyo (JP)

Primary Examiner—Ralf Seifert

(**) Term: **14 Years**

(74) Attorney, Agent, or Firm—Bell, Boyd & Lloyd LLC

(21) Appl. No.: **29/172,798**

(57) **CLAIM**

(22) Filed: **Dec. 17, 2002**

The ornamental design for a belt adjuster, as shown and described.

(30) **Foreign Application Priority Data**

Jun. 18, 2002 (JP) 2002-016329

DESCRIPTION

(51) **LOC (7) Cl.** **02-07**

FIG. 1 is a perspective view of a belt adjuster of the claimed design.

(52) **U.S. Cl.** **D11/218**

FIG. 2 is a front elevational view of the belt adjuster of FIG. 1.

(58) **Field of Search** D11/200, 215–218,
D11/212; 24/196–198, 200

FIG. 3 is a cross-sectional view taken along the line 3—3 of the belt adjuster of FIG. 2.

(56) **References Cited**

FIG. 4 is a cross-sectional view taken along the line 4—4 of the belt adjuster of FIG. 2.

U.S. PATENT DOCUMENTS

FIG. 5 is a rear elevational view of the belt adjuster of FIG. 1.

D340,008 S * 10/1993 Anscher D11/218
D421,578 S * 3/2000 Anscher D11/218
D467,838 S * 12/2002 Yoshiguchi D11/218

FIG. 6 is a top plan view of the belt adjuster of FIG. 1.

FOREIGN PATENT DOCUMENTS

FIG. 7 is a bottom plan view of the belt adjuster of FIG. 1; and,

JP 778140 12/1989
JP 778140-1 1/1990
JP 936320 10/1995

FIG. 8 is a right side view of the belt adjuster of FIG. 1, and the left side view is a mirror image thereof.
